UNITED STATES PATENT OFFICE.

GEORGE M. BENNETT, OF KENOSHA, WISCONSIN, ASSIGNOR OF ONE-HALF TO THOMAS FORGHAM, OF KENOSHA, WISCONSIN.

COAL UNLOADING AND DISTRIBUTING APPARATUS.

No. 895,064.

Specification of Letters Patent.

Patented Aug. 4, 1908.

Application filed October 15, 1906. Serial No. 338,937.

To all whom it may concern:

Be it known that I, GEORGE M. BENNETT, a subject of Great Britain, residing at Kenosha, in the county of Kenosha and State of Wisconsin, have invented a new and useful Improvement in Coal Unloading and Distributing Apparatus, of which the following is a specification.

The present invention constitutes an improvement upon the coal unloading and distributing apparatus for use in ballast burning described and claimed in Letters Patent No. 633,348, granted September 19, 1899, to Z. G. Simmons, Jr., T. Forgham and G. M. Bennett.

The invention is illustrated in its preferred embodiment in the accompanying drawings, in which—

Figure 1 is a broken view in side elevation, of the side opposite that on which the coal is to be unloaded, of the improved coal unloading and distributing apparatus; Fig. 2, a plan view of the same; Fig. 3, a section through the coal car looking toward the transferring car, as indicated at line 3 of Fig. 1; Fig. 4, a broken vertical section through the transferring car taken as indicated at line 4 of Fig. 1; Fig. 5, a view in side elevation similar to Fig. 1, but showing the complete apparatus and illustrating how the same is made up into a train; Fig. 6, an end elevational view of the car in advance of the coal car shown in Fig. 5 and which serves to support one end of the shovel-supporting cable; Fig. 7, a plan sectional view taken approximately as indicated at line 7 of Fig. 4; Fig. 8, a view showing the lateral conveyer equipped with a modified form of shiftable chute at its outer end; Fig. 9, a cross-sectional view of the lateral conveyer taken as indicated at line 9 of Fig. 10; and Fig. 10, a broken plan view of said lateral conveyer.

In the construction illustrated, 1 designates a transferring and distributing car; 2, a coal car; 3, a cable car; and 4, an engine.

The cars and engine are coupled together in the order named, and the train thus formed is supported on a track 5, which, in practice, extends parallel with and adjacent to the banks of burning ballast.

The transferring car 1 may be of any suitable construction, so far as the formation of the body of the car is concerned. Preferably said car and the attendant mechanism comprise an ordinary flat-car upon which is

erected a body A which is provided with lateral openings a; a lateral conveyer B extending through the openings a at one side of the body A and supported on a pivot b at the other side of said body, said conveyer being equipped with an endless conveyer chain B¹ and provided at its end with a pivoted adjustable chute B² adapted to be raised and lowered relative to the conveyer; a hopper C centrally supported in the car-body above the lower inner end of the lateral conveyer; a chute C¹ leading from the front end of the transferring car to the hopper and having an adjustable section C² adapted to form a bridge-piece from the transferring car to the coal car, said bridge-piece being supported at its rear end by chains c and at its front portion by cables c¹ passing over pulleys c² equipped with weights c³; a conveyer-supporting mast D comprising upwardly converging members d connected by hinges d¹ with the upper timbers d² of the car-body; a relatively short cable-supporting mast E comprising upwardly converging timbers e connected with the frame-members d² by hinges e¹ in the rear of the hinges d¹; a shovel-supporting cable F passing over a pulley f at the top of the mast E and joined to a winding drum f¹ (Fig. 7); a draw-cable G passing about a pulley g at the base of the mast E and to a winding drum g¹ (Fig. 7); and a motor H geared to said drums and to the endless conveyer chain B¹ in a manner now well understood in the art.

The cable F supports a traveling shovel I which has a bail or draft member i connected with the draft-cable G. The shovel may be of any suitable construction, the one illustrated being the one shown in detail in the above-mentioned patent.

Upon the car 3 is located a mast J equipped at its apex with a transversely extending shaft j with which is connected a transversely shiftable hook j² connected with the end of the cable F.

The details of construction of the car A are preferably, in the main, the same as those described in the above-mentioned patent, and it will be unnecessary to repeat the description here.

The outer end of the frame of the lateral conveyer B is connected by cables, or rods, b¹ to the upper end of the mast D, it being observed that the mast D is located centrally above the inner end of the conveyer.

The conveyer-frame is braced against swaying laterally by guys b^2 b^3 connected with one of the timbers d^2 of the car-body. The lateral strain exerted upon the mast D by the weight of the conveyer is provided against by the guy b^4 connected with a timber b^5 projecting laterally from the opposite timber d^2 of the car-body, and which has its outer end connected by a guy b^6 with the lower portion of the car-body. Beneath the plane of timber b^5 are laterally projecting timbers b^7 which serve to support ballast b^8 acting as a counter-balance to the conveyer. The outer end of the frame of the lateral conveyer supports a standard b^9 having its upper end connected by guys b^{10} with the conveyer frame at a distance from its outer end. The chute B^2 is joined by a pivot b^{11} to the conveyer-frame near its outer end, and has its free end equipped with hooks b^{12} engaged by chains b^{13} connected with the upper end of the standard b^9 . Thus, the chute is adjustable with relation to the outer end of the conveyer. The sides of the chute diverge or expand toward the free end of the chute, and the bottom of the chute is provided with cleats b^{14} which diverge toward the free end of the chute. The purpose of this divergence is to effect a wider distribution or spreading of the coal upon the ballast bank.

The mast E is sufficiently shorter than the mast D to permit the shovel-supporting cable F to pass freely between the upwardly convergent members d of the mast D. The mast E is connected by guy rods e^1 e^2 with the rear portion of the car-body A, and is connected by guy rods e^3 e^4 with the mast D. The mast D is connected by guy rods d^3 d^4 with the front end of the car-body A. The pivot of the mast E is in a somewhat higher plane than the pivot of the mast D, so that the mast D may be lowered and allowed to rest upon the top of the car-body A and the mast E lowered and allowed to rest upon the mast D.

The shovel-supporting cable F preferably has its front end shiftably connected with the transverse shaft j of the mast J, but it will be understood that while this arrangement possesses advantages, other convenient arrangements may be made. The mast J is preferably some distance in front of the rear end of the car 3, being shown, in fact, at the front end of the car 3. The arrangement is such that the shovel may be shifted laterally without difficulty to facilitate the taking of the coal from the sides of the coal car. This action is facilitated by the movability of the hook j^1 , but this feature is not an essential feature.

In operation, the winding drums g^1 f are operated to bring the shovel I to the desired position over the coal car 2, whereupon the cables are slackened to permit the shovel to

drop into the coal car, after which the draw-cable G is operated to draw the shovel through the coal, causing it to be filled, after which it is drawn up the inclined chute to the hopper C, from which it passes to the lateral conveyer B. From the outer end of the conveyer chain B¹ the coal is delivered upon the inclined chute B² by which it is distributed upon the ballast bank, the adjustment of the chute B² being varied from time to time to secure the most economical distribution, according to variations or irregularities in the ballast bank. The completion of the distribution upon the ballast bank is effected by shovelers, the distribution of the coal upon the inclined surface of the bank by the conveyer being so regulated as to enable the shovel to be aided by gravity in doing such shoveling as may be necessary by manual labor.

In the operation of the apparatus, it will be observed, the coal car 2 forms a rigid connecting link between the cable-supporting car 3 and the transferring car 1, and, in practice, the cables F and G are always made of sufficient length to enable the coal car of any length to be inserted between the cars 1 and 3. Thus, the apparatus is adapted to the varying conditions in modern railway practice without rendering the apparatus unwieldy. By the employment of the car 3 with the mast J erected thereon, the necessity for a forwardly projecting boom is dispensed with, and the necessity for exceedingly strong and heavy construction in the transferring car is obviated. Moreover, the apparatus is rendered more easy of transportation. Likewise, the provision of the adjustable chute B² upon the outer end of the lateral conveyer enables such a distribution of the coal upon the horizontal and sloping portions of the ballast bank to be effected by raising and lowering the free end of the chute as to render it highly economical to dispense with the lateral shovelers' platform which has heretofore been employed, thereby greatly reducing the weight to be supported at a great distance from the side of the car and enabling the length of the lateral conveyer to be correspondingly increased. Thus the range of the transferring car in effecting distribution of the coal upon the ballast bank is greatly increased.

In Fig. 8, the lateral conveyer is shown equipped with an oscillating double-incline chute B³, which replaces the chute B² shown in Figs. 2 and 3. The chute B³ is A-shaped, being supported beneath its apex on a shaft b^{15} journaled in brackets b^{16} (one shown) depending from the outer end of the conveyer-frame. The chute is firmly fixed to the shaft, and the shaft is equipped with an arm b^{17} , joined by a connecting-rod b^{18} to a wrist-pin b^{19} on a gear b^{20} which meshes

with a pinion b^{21} on the conveyer-shaft b^{22} at the outer end of the conveyer. As the gear b^{20} is driven through the medium of the endless conveyer-chain B^1 , the shaft b^{22} 5 and pinion b^{21} , the chute is caused to oscillate back and forth through an angle of 180° , thereby causing the coal to be sprinkled upon the inclined face of the ballast-bank for a distance of many feet beyond 10 and many feet within the outer end of the conveyer B .

As shown in Figs. 9 and 10, the conveyer-frame is provided with a bottom comprising sections b^{23} , b^{24} , b^{25} , b^{26} , the first or inner one 15 of which is solid or imperforate, the second of which has closely spaced longitudinal rods forming a comparatively fine screen, the third of which has more widely spaced rods, and the fourth or outer one of which 20 has still more widely spaced rods. Thus the conveyer bottom is so constructed that no coal can drop therethrough at the innermost section (spanning the ditch), fine coal can drop upon the lower portion of the 25 inclined shoulder of the bank and successively larger lumps can fall upon the bank as the outer end of the conveyer is approached. The result of this arrangement is to distribute the coarser lumps of coal 30 where they are most needed to insure proper draft and proper distribution of the heat, it being understood that there are naturally a larger or deeper body of burning material and more heat near the base of the bank 35 than there is near the top of the bank. The conveyer-frame has the usual obliquely set or upwardly diverging side-boards b^{27} . The endless conveyer-chain moves in the direction indicated by the arrows in Figs. 40 4 and 8.

The foregoing detailed description has been given for clearness of understanding only, and no undue limitation is to be understood therefrom.

45. What I regard as new, and desire to secure by Letters Patent, is—

1. In coal transferring apparatus, the combination of a transferring car equipped with a lateral conveyer, a shovel-supporting cable disposed to permit a shovel to pass from the coal car adjacent to one end of the transferring car and deliver coal to said lateral conveyer, a shovel connected with the supporting cable, a draft-cable, and a separate car 50 equipped with means for supporting one portion of the supporting cable, for the purpose set forth.

2. In coal transferring apparatus, the combination of a coal transferring car equipped 60 with a lateral conveyer, a mast on said car equipped with a pulley, a shovel-supporting cable passing over said pulley, a shovel supported on said cable, a draw cable attached to said shovel, a pulley on said car over 65 which said draw cable passes, and a separate

car equipped with means for supporting one portion of said shovel-supporting cable, said cars adapted to receive a car between them.

3. In coal transferring apparatus, the combination of a car equipped with a lateral conveyer, a mast on said car equipped with a pulley, a shovel-supporting cable passing over said pulley, a shovel supported on said cable, a draw cable connected with said shovel, a pulley supported on said car over which said 70 draw cable passes, means on said car for operating said cables and said lateral conveyer, and a separate car equipped with means for supporting one portion of said shovel-supporting cable. 75

4. In coal transferring apparatus, the combination of a transferring car, pulleys supported thereon, a shovel-supporting cable and a draw cable passing over said pulleys, a lateral conveyer supported on said car, 80 means supported on said car for operating said cables and said lateral conveyor, a shovel supported on said first-named cable, a second car to which said shovel-supporting cable extends, and a laterally shiftable connection between said shovel-supporting cable and said second-named car. 85

5. In coal transferring apparatus, the combination of a transferring car, pulleys supported thereon, a shovel-supporting cable 90 and a draw cable passing over said pulleys, means supported on said car for supporting said cables, a shovel supported on said first-named cable and attached to said second-named cable, and a second car equipped with 95 a mast connected with said shovel-supporting cable.

6. In coal transferring and distributing apparatus, the combination of a transferring car, a lateral conveyer supported on said 100 transferring car, means for delivering coal from the coal car to said lateral conveyer, and a movable chute pivotally connected with the outer end of said lateral conveyer and serving to receive the coal therefrom, for 105 the purpose set forth.

7. In coal unloading and distributing apparatus, the combination of a transferring car, a conveyer supporting mast erected thereon, a lateral conveyer having a frame 110 connected at its inner end with the body of said car, connecting means joining the outer end of the conveyer frame to the upper end of said mast, a cable-supporting mast in the rear of said first-named mast and equipped 115 below the upper end of said first-named mast with a pulley, a shovel-supporting cable passing through said first-named mast and over said pulley, a draw cable, means supported on said car for operating said cables 120 and said conveyer, and a shovel connected with said cables.

8. In coal transferring and distributing apparatus, the combination of a transferring car, a conveyer supporting mast pivoted 125

thereon at a given point, a cable-supporting mast in the rear of said first-named mast and pivoted on said car at a higher point, guy rods connecting said masts with said car, a lateral conveyer having a frame connected at its inner end with the body of said car, means connecting the outer end of said conveyer-frame with the upper end of said first-named mast, a shovel supporting cable passing through said first-named mast, a pulley supported on said second-named mast below the upper end of said first-named mast and over which said cable passes, a draw cable, means mounted on said car for operating said cables and said lateral conveyer, and a shovel supported on said first-named cable and connected with said second-named cable.

9. In coal unloading and transferring apparatus, the combination of a transferring car, a lateral conveyer supported thereon, means for transferring coal from a coal car to said lateral conveyer, and a movable chute pivotally connected with the outer end of said conveyer.

10. In coal unloading and distributing apparatus, the combination of a transferring car, a lateral conveyer supported thereon, means for transferring coal from a coal-car to said lateral conveyer, and an oscillating

chute connected with the outer end of said conveyer.

11. In coal unloading and distributing apparatus, the combination of a transferring car, a lateral conveyer supported thereon, means for transferring coal from a coal-car to said lateral conveyer, and a double-incline chute movably connected with the outer end of said conveyer and having its apex presented to the outer end of said conveyer.

12. In coal unloading and distributing apparatus, the combination of a transferring car, a lateral conveyer supported thereon, means for transferring coal from a coal-car to said lateral conveyer, and an oscillating double-incline chute carried by said conveyer and having its apex presented to the outer end of said conveyer.

13. In coal unloading and distributing apparatus, the combination of a car, a lateral conveyer supported thereon and equipped with an endless conveyer-chain, and a swinging chute connected with the outer end of the conveyer and actuated from said conveyer-chain.

GEORGE M. BENNETT.

In presence of—

A. N. THORIEN,
C. W. WASHBURN.
